ATTORNEY.

UNITED STATES PATENT OFFICE.

HORACE T. HELMBOLD, OF PHILADELPHIA, PENNSYLVANIA.

TOY TRUNDLE.

SPECIFICATION forming part of Letters Patent No. 249,521, dated November 15, 1881.

Application filed September 22, 1881. (No model.)

To all whom it may concern:

Be it known that J. HORACE T. HELMBOLD, a citizen of the United States, residing in the city and county of Philadelphia, and State of Pennsylvania, have invented a new and useful Improvement in Toy Trundles, which improvement is fully set forth in the following specification and accompanying drawings, in which—

Figure 1 is a side elevation of the toy trundle embodying my invention. Fig. 2 is a longitudinal section of a portion thereof, enlarged.

Similar letters of reference indicate corresponding parts in the two figures.

My invention consists of a toy trundle formed of a ground-wheel with a toothed periphery, a spring-tongue engaging with the periphery thereof, and a handle, whereby, when the trundle is rolled, the wheel will be rotated without slipping, and the tongue snapped, so as to create a rattling sound, thus increasing the amusing nature of the toy.

Referring to the drawings, A represents the handle of the toy, on the forward end of which is mounted the wheel B, whose periphery *a* is serrated, scalloped, corrugated, serpentine, or otherwise constructed of ratchet or toothed form.

C represents a spring strip or tongue, which has one end connected to the handle near the wheel B, and the other end disposed in contact with the toothed periphery of said wheel.

It will be seen that when the trundle is rolled the wheel B runs on the ground, pavement, &c., as usual, and, owing to the peripheral teeth of said wheel, the tongue C is first raised and then caused to drop abruptly in the space or depression between adjacent teeth, or snapped, whereby a rattling sound is occasioned, which adds to the amusing nature of the toy.

It will also be seen that the toothed periphery of the wheel takes firmly hold of the ground, &c., whereby slipping of the wheel is prevented, and as the entire device may be made of wood a strong and cheap toy may be produced, it being noticed that the toothed periphery of the wheel is not only adapted for caus-

ing the snapping of the spring-tongue, but also for taking hold of the ground and reliably causing rotation of the wheel regardless of the resistance offered by said spring-tongue. 50

The tongue may be secured to the handle so as to project either tangentially or radially to the periphery of the wheel. In either case the length of the tongue is insufficient to act as a stop and prevent rotation of the wheel in reversed directions. By this provision the rattling sound of the toy may be caused, whether the trundle is run forward or backward. 55

I am aware that it is not new to form a toy of a ground-wheel with inserted pins projecting from its side and a snapping-spring engaging therewith; but my device has the following advantages thereover: The ground-wheels may be cheaply constructed of a block of wood sawed or grooved into toothed shape and then sliced into pieces the required thickness of the wheels, thus forming the body of the wheel and the toothed periphery thereof. My wheel takes hold of the ground and does not slip, and thus more easily overcomes the pressure of the 70 spring-tongue. Furthermore, the toy may be rolled backward and forward and the snapping or rattling sound thereby occasioned in reverse directions of the wheel.

Having thus described my invention, what 75 I claim as new, and desire to secure by Letters Patent, is—

1. The toy trundle consisting of a ground-wheel, a snapping-tongue, and a handle, said wheel having a toothed periphery, on which 80 the toy is rolled, and said tongue engaging with said toothed periphery, substantially as and for the purpose set forth.

2. The toy trundle having a toothed wheel and a snapping-tongue, the latter engaging 85 with the periphery of the former and operating in reversed directions thereof, substantially as and for the purpose set forth.

HORACE T. HELMBOLD.
